UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

FLUID COMPRESSOR.

Application filed August 4, 1921. Serial No. 489,702.

To all whom it may concern:

Be it known that I, CHESTER W. METZGAR, a citizen of the United States, and a resident of Easton, county of Northampton, 5 and State of Pennsylvania, have invented a certain Fluid Compressor, of which the following is a specification, accompanied by drawings.

This invention relates to compressors, but 10 more particularly to a compressor for compressing gas with varying discharge pressures.

In pumping gas, for instance, from a gas bell operated from any suitable source, for 15 use at a remote point, as in a city supply, the condition arises in which the compressor shall continue to operate for a short time, without however, pumping gas from the gas bell. Otherwise continuous pumping 20 would drain down the gas in the bell to an undesirable point.

A regulator of the type disclosed in my co-pending application, Serial No. 489,626 filed Aug. 3, 1921, has been selected to illustrate 25 the invention, which regulator will unload the compressor step by step according to successive changes in the predetermined line pressure, and will completely unload the compressor at this pressure as usual 30 with this type of regulator.

The object of the present invention is to enable the compressor to be completely unloaded with smaller clearance pockets than are required with the ordinary way of unloading. In accordance with this invention, 35 I provide operative means for utilizing a portion of the bore of one end of one cylinder as a clearance space for the other cylinder for unloading the compressor. One end 40 of either cylinder may be utilized as a clearance space for the other cylinder.

The invention is shown in one of its preferred forms in the accompanying drawings, in which

45 Figure 1 is a diagrammatic view partly in longitudinal section of a portion of a compressor embodying the invention,

Figure 2 is an enlarged detail longitudinal sectional view of one of the clearance 50 valves,

Figure 3 is an end elevation of the compressor, and

Figures 4 to 7 inclusive, are diagrammatic views showing the relative positions of the

pistons in the two cylinders during a complete revolution of the crank shaft.

Referring to the drawings, the compressor may be of any suitable type, but I have chosen for illustrative purposes to show a single stage duplex compressor having two low pressure cylinders A and C and two double acting pistons B and D. The pistons, having the piston rods E and F may be driven from any suitable source or sources of power (not shown) and the cylinders are provided respectively with clearance pockets G and H, and J and K, communicating with the cylinders and controlled by suitable clearance valves T contained in the valve casings 1, 2, 3 and 4, 60 mounted on the heads O and P of the cylinder A, and similar valves T in similar valve casings 1, 2, 3, and 4, mounted on the air heads Q and R of the cylinder B. The compressor valves S for the cylinder A 65 and the valves U for the cylinder B, which may be of the plate type, are mounted in the air heads and serve as inlet or discharge valves in the usual manner. The compressor cylinders are assumed to be connected 70 by suitable piping to each other and to the main receiver V, the piping not being shown for the sake of simplicity. The chambers W in the air heads, in which the clearance valves T operate, communicate 75 with the various clearance pockets G, H, J and K in the cylinders A and C, by means of the ports X, and the corresponding pockets for opposite ends of the cylinder are in this instance connected by cross 80 connections Y, communicating with the clearance pockets through the ports Z and controlled by by-pass valves a operating in the casings 5 and 6.

The clearance valves T are similar to the by-pass valves a, and are preferably of the construction shown in detail in Figure 2, in which the valve seat b is provided with a guide c, over which the hollow head d of a valve T or a slides, and upon which the valve is guided. A spring e, compressed between the guide c and the valve head d, tends to open the valve when line pressure from the receiver C, which tends to close the valve, is relieved. A pin f passing through a stuffing box g bears against the valve head b and against the piston h operating in the piston chamber j. Receiver pressure is sup-

plied to the chamber *j* behind the piston *h* through a suitable pipe connection. The by-pass valves *a* are provided with manual means for rendering the valve inoperative, 5 by holding them closed and for this purpose the valve casings 5 and 6 are provided with adjustable set screws *k* in the casing heads *o*. The set screws may be provided with squared ends *p* and lock nuts *q* and 10 when a set screw is screwed in a sufficient distance, the piston *b* will be forced inwardly and the by-pass valve will be maintained closed.

The clearance valves *T* and the by-pass 15 valves *a* are all adapted to be maintained in closed position by receiver pressure from the receiver *V*, and the valve casings are all connected by suitable pipe connections to the valve chest *r* of a regulator *s*, of the 20 type described in my copending application, Serial No. 489,626 filed August 3, 1921. This regulator operates in substantially the same manner as the regulator disclosed in United States Patents No. 1,027,757; 25 1,027,758; and 1,027,760, granted May 26, 1912, to William Prellwitz, assignor to Ingersoll-Rand Company. In such a regulator the movements of a plurality of main regulating valves within the valve chest *r* 30 for controlling the loading and unloading of the compressor, are in turn controlled by an auxiliary regulator valve within the valve chest *r*. With such a regulator, clearance pockets of the compressor are brought 35 into and out of communication with the interior of the compressor cylinders, for securing a step by step unloading or loading of the compressor as the fluid in the main receiver tank *V* reaches successively attained pressures.

Without describing the internal construction of the regulator *s* it is sufficient for the purposes of this invention to describe the mode of operation. The valve casings 1, 2, 45 3 and 4 of the cylinder *A* are connected to the similarly numbered valve casings 1, 2, 3 and 4 of the cylinder *B* by means of the pipes 1^a, 2^a, 3^a and 4^a, which are in turn connected by branch pipes 1^b, 2^b, 3^b and 4^b 50 to the valve chest *r* of the regulator *s*, so that the clearance valves *T* are operated in pairs. The valve casings 5 and 6 of the by-pass valves *a* are connected by branch pipes 5^a and 6^a direct to the valve chest *r* 55 of the regulator *s*, and the construction is such that when the last pair of clearance valves *T* in the valve casings 4 is opened, in the successive step by step operation of the unloading, by relieving the pressure behind the heads of said clearance valves *T*, the by-pass valves *a* operating in the casings 60 5 and 6 are opened one after the other in order to open communication between the opposite clearance pockets *G* and *J*, and *H* 65 and *K*. The last step of unloading is ef-

fected by the opening of the by-pass valve *a* operating in the valve casing 6.

Before describing the manner in which one end of one cylinder is utilized as a clearance space for the other cylinder, in accordance with the diagrams of Figures 4 to 7 inclusive, the remainder of the regulating apparatus will be described. The valve chest *r* of the regulator *s* is connected by a pipe *t* to the pipe *u*, which connects the receiver tank *V* to casing *v* of a fluid actuated device, having a lever arm *w* adapted to be connected by means of a rod *x* to the auxiliary controlling valve of the regulator *s*. The lever *w* is pivoted at *y* on the frame 80 *v* and the weight of the lever is carried on a pin *z*, movable in any suitable manner in accordance with successively attained receiver pressures. The end of the lever *w* may be weighted by the weights 2^e and a 85 rod 3^e pivoted at 4^e to the lever *w* extends through the frame of the device and is provided with a cap 5^e between which and the frame, the spring 6^e is compressed for resisting upward movement of the lever. 90 Fluid pressure is exhausted from the valve chest *r* through the exhaust pipe 8 communicating with the bottom of the valve chest, and exhaust pipe 9 communicating with the top of the valve chest through the frame *v* 95 of the controlling device. In the position of the parts indicated in Figure 1, the controlling lever *w* has been raised by fluid pressure in the receiver tank *V* to its uppermost position in which case, pressure has 100 been relieved from behind the heads or pistons *h* of all the clearance valves *T* and the two by-pass valves *a*, so that all of said valves have been successively automatically opened, and the compressor is completely 105 unloaded.

Referring more particularly to Figures 4, 5, 6 and 7, obviously, if desired, the by-pass valves *a* may be hand operated valves having the handles 10 and 11 for manual 110 operation, instead of automatic operation, as shown in Figure 1. In the operation of the apparatus, let it be assumed that all the clearance valves *T* and the two by-pass valves *a* are open. In Figure 4 the pistons 115 *B* and *D* are moving in the same direction as indicated by the arrows and compressing from intake pressure to discharge pressure for only one half of a stroke.

In Figure 5 the pistons *B* and *D* are 120 through with compression, with the gas in the clearance spaces at discharge pressure. The clearance spaces consist of substantially one half of the compression space of one end 12 of the cylinder *A*, and the clearance 125 pockets *H* and *K* in both cylinders, because the space 12 of the cylinder *A* is in communication with the pockets *K* of the cylinder *C* through the cross connection *Y*.

The pistons *B* and *D* then move in oppo- 130

site directions for one half of a stroke, displacing the gas in the space 12 of the cylinder A until the position of Figure 6 is reached, the pressure remaining constant.

5 The gas from the space 12 of the cylinder A has been displaced to the space 13 of the cylinder C.

In Figure 6 the pistons B and D are through with displacement and are about to 10 move in the same direction, for one half of a stroke, but opposite to the direction indicated in Figure 4. The gas in the clearance pockets H and K of both cylinders and in the space 13 of the cylinder C, is expanded from discharge pressure to intake 15 pressure.

In the position of the pistons B and D in Figure 7, the gas is through with expansions, and the travel of the piston D is about 20 to reverse so that the pistons will be moving in opposite directions for one half of a stroke, displacing the gas at intake pressure from the cylinder C to the cylinder A.

The displacement of gas from one cylinder to another described in connection with the spaces 12 and 13 at one end of the cylinders takes place in a similar manner for the spaces 14 and 15 at the opposite ends of the cylinders. Displacement of gas takes 30 place twice in each cylinder and for each revolution of the compressor.

I claim:

1. In a fluid compressor, the combination 5 of two cylinders and pistons reciprocating therein, and means operable for utilizing a portion of the bore at one end of one cylinder as a clearance space for the other cylinder for unloading the compressor.

2. In a fluid compressor, the combination 40 of two cylinders and pistons reciprocating therein, and means operable for utilizing a portion of the bore at one end of either cylinder as a clearance space for the other cylinder for unloading the compressor.

45 3. In a fluid compressor, the combination of two cylinders and double acting pistons reciprocating therein, and means operable for utilizing portions of the cylinder bores at both ends of either cylinder as clearance 50 spaces for the other cylinder for unloading the compressor.

4. In a fluid compressor, the combination 55 of two cylinders having clearance pockets adapted to be placed in communication with the cylinders respectively, pistons reciprocating in the cylinder bores, and means operable for utilizing a portion of the bore at one end of one cylinder as an additional clearance space for the other cylinder for unloading 60 the compressor.

5. In a fluid compressor, the combination 65 of two cylinders having clearance pockets adapted to be placed in communication with the cylinders respectively, pistons reciprocating

ing in the cylinder bores, and means operable 65 for utilizing a portion of the bore at one end of either cylinder as an additional clearance space for the other cylinder.

6. In a fluid compressor, the combination 70 of two cylinders having clearance pockets adapted to be placed in communication with the cylinders respectively, double acting pistons reciprocating in the cylinder bores, and means operable for utilizing portions of the cylinders bores at both ends of either cylinder 75 as additional clearance spaces for the other cylinder for unloading the compressor.

7. In a fluid compressor, the combination 80 of two cylinders and double acting pistons reciprocating therein and means operable for utilizing portions of the cylinder bores at opposite ends of either cylinder as clearance spaces for corresponding ends of the other cylinder for unloading the compressor.

8. In a fluid compressor, the combination 85 of two cylinders having clearance pockets adapted to be placed in communication with the cylinders respectively, double acting pistons reciprocating in the cylinder bores, and means operable for utilizing portions of the 90 cylinder bores, at opposite ends of either cylinder as additional clearance spaces for corresponding ends of the other cylinder for unloading the compressor.

9. In a fluid compressor the combination 95 of two cylinders and pistons reciprocating therein, a connection independent of the discharge line affording communication between the compression spaces of the cylinder bores and means for controlling said connection, 100 whereby a portion of the compression space of one cylinder may be utilized as the clearance space for the other cylinder for unloading the compressor.

10. In a fluid compressor, the combination 105 of two cylinders and pistons reciprocating therein, cross connections independent of the discharge line affording communication between the compression spaces of the cylinder bores, and means for controlling said connections 110 whereby portions of the compression spaces of the cylinders may be utilized as the clearance spaces for unloading the compressor.

11. In a fluid compressor, the combination 115 of two cylinders and double acting pistons reciprocating therein, connections independent of the discharge line affording communication between the compression spaces at corresponding ends of the cylinder bores, 120 and means for controlling said connections, whereby the compression spaces of either cylinder bore may be utilized as clearance spaces for either end of the other cylinder for unloading the compressor.

In testimony whereof I have signed this specification.

CHESTER W. METZGAR.
